Term of patent 14 years

(Cl. D34—15)

To all whom it may concern:

Be it known that I, Harry Sebel, a subject of the King of Great Britain, resident of London, England, have invented a new, original, and ornamental Design for a Wheeled Toy Figure or the like, of which the following is a specification, reference being had to the accompanying drawing, forming part thereof.

I claim:

The ornamental design for a wheeled toy figure or the like, as shown.

HARRY SEBEL.
